(57) **CLAIM**

The ornamental design for a golf-ball shaped ashtray, as shown and described.

DESCRIPTION

FIG. 1 is a top and front perspective view of a golf-ball shaped ashtray showing my new design with the ashtray being shown in a partially open position;

FIG. 2 is a top and side perspective view thereof;

FIG. 3 is a side perspective view thereof with the golf-ball shaped ashtray being shown in a fully opened position; and,

FIG. 4 is a side perspective view thereof with the golf-ball shaped ashtray being shown in a fully opened position.

The golf-ball shaped ashtray includes top and bottom hollow

parts that mate together and each has an exterior dimpled

surface.

The broken lines shown in the drawings illustrate portions of

the golf-ball shaped ashtray that form no part of the claimed

design.
